Primary Examiner — Ian Simmons*Assistant Examiner* — Dana L Meyrow*(74) Attorney, Agent, or Firm* — Staas & Halsey LLP(57) **CLAIM**

I claim the ornamental design for a bottle, as shown and described.

DESCRIPTION

FIG. 1 is a front top, perspective view of the bottle showing my design;

FIG. 2 is a front view thereof, the rear view being identical;

FIG. 3 is a left side view thereof, the right side being identical;

FIG. 4 is a top view thereof; and,

FIG. 5 is bottom view thereof.

The dot-dot-dash broken line in the FIG. 5 drawing view defines the bounds of the claim and forms no part thereof.
